J. M. May,

Wind Wheel,

No 22,965.

Patented Feb. 15, 1859.

UNITED STATES PATENT OFFICE.

JOHN M. MAY, OF JANESVILLE, WISCONSIN.

IMPROVEMENT IN WINDMILLS.

Specification forming part of Letters Patent No. 22,965, dated February 15, 1859.

To all whom it may concern:

Be it known that I, JOHN M. MAY, of Janesville, in the county of Rock and State of Wisconsin, have invented a new and useful Improvement in Constructing Windmills and in Regulating and Controlling the Same; and I do hereby declare that the following is a full, clear, and exact description of the same, reference being had to the accompanying drawings, forming a part of this specification, the same letters of reference indicating the same parts in each figure.

The nature of my invention consists in the peculiarly-constructed stationary central vertical shaft, in combination with the peculiarly-constructed hollow tubular shaft or column placed over and revolving freely around it. This central column is so formed that it serves as axes for the axle of the wind-wheel and the tubular column to revolve upon in the path of horizontal circles and serving also as a support and guide for the entire structure, while the tubular column serves for receiving power from the wind-wheel and transmitting it to machinery, whereby is obviated the necessity of any frame-work whatever to support the wind-wheel.

It consists, second, in forming the axle of the wind-wheel with a shoulder in the form of a hub or pipe box to receive the upper end of the vertical shaft as an axis and bearing for the horizontal revolutions of the wind-wheel, the center of the axes of the shaft and axle intersecting and furnishing in themselves central axes and bearings inside of the angle of the gear-wheels on the vertical shaft and horizontal axle, the shaft and axle also serving as axes and bearings for the gear-wheel, enabling them to operate freely with each other as the wind-wheel is revolved to different points of the compass as the wind changes, and the use of a turn-table outside of the gear-wheels wholly obviated.

It consists, third, in providing a governing-rod (steadied by a guide-bar) forked at its upper end to fit the horizontal groove in a sliding thimble on the vertical column and the lower end jointed to a horizontal lever (that may be weighted) for controlling and regulating the wind-wheel.

It consists, fourth, in providing a conical covering for the mechanism in the wind-wheel

head to protect it from the elements and divide the wind-current and guide it onto the sails, and to protect the governors from the countervailing influence of the wind-current in regulating the velocity of the wind-wheel.

To enable others skilled in the art to make and use my invention, I will proceed to describe its construction and operation.

Figure 1 is a perspective drawing of a mill ready for use, but without the covering or roofing to protect the mechanism, and for other purposes, as seen in Figs. 2 and 6. Fig. 2 is a vertical section on a plane through the axes of the vertical shaft and horizontal axle. Fig. 3 is a detail drawing of the groove-thimble, showing their connection with the double-forked elbow-lever. Figs. 4 and 5 are sections of parts of the vertical shaft and horizontal axle that take the place of or serve instead of a turn-table and furnish bearings for the gear-wheels, and Fig. 6 is a perspective view of the conical covering detached from the machine.

A in Figs. 1 and 2 is the center part or column, the lower end of which is made firm to a beam, timber, or pedestal U, and has a shoulder b at or near its base, which serves as a vertical and horizontal bearing for the tubular shaft or column to rest and revolve upon. Toward the upper end of the shaft A and a short distance above the top of the tubular column is another shoulder-bearing c, formed on the shaft A, above which the shaft still extends and serves as a vertical axis for the horizontal axle for the wind-wheel, and on which shoulder and axis the axle of the wind-wheel rests and revolves.

B is a tubular or hollow column fitting easily over the center shaft A and has its lower bearing at b. The vertical position of this bearing on the center shaft extends upward a short distance, sufficient to meet the lateral pressure and friction of a drum band-wheel or gear-wheels in attaching to other machinery. Thence upward there is a space between the shaft A and tubular column B until near and at the top of the column a bevel cog gear-wheel is fastened to the tubular column, where there is a vertical bearing on the shaft A to meet the friction caused by the gear-wheels. Thus the tubular column is caused to run lightly as it revolves around

the center shaft A. This tubular column receives motion from the wind-wheel by gear-wheels at or near its upper end and communicates it by band or gear wheels near its lower end or at any point along its length.

C is a horizontal axle formed with a tube-box c and fits easily the vertical axis d, formed of the upper part of the shaft A, and rests and revolves on the shoulder-bearing a. The front part of this axle forms the arm or axis on which the wind-wheel revolves, and the rear part of this axle is formed into a stem f of the vane W, which guides the wind-wheel to the wind-current as the wind changes to different points of the compass. This axle also has a projection H, which serves as a fulcrum and support for the double-forked elbow-lever I, the uses of which will presently appear.

The shoulder a being a little distance above the column B, both the axle C and column B revolve around the shaft A with perfect freedom and independently of each other.

The wind-wheel itself is composed mainly of the pipe-box N, hub K, and head J, which are built firmly together. On the end of the pipe-box opposite the head J the gear cog-wheel E is fastened. The other parts of the wind-wheel are the elbows L, with one arm O bearing the governor-balls P and the other arm forming the stems of the sails M, and also serve as radial axes in revolving the sails in their bearings in the hub K and head J, the elbows being connected to the sliding thimble F by the bars V, which are jointed to each. This thimble fits the pipe-box N easily, and, as it is moved back and forth, revolves the sails on their respective stems; also, on the end next to the cog-wheel this thimble has a groove around its circumference to receive the curved points of the vertical arm of the elbow-lever I.

G is another thimble fitting easily around the tubular shaft B, on which it is moved vertically, having two grooves around its circumference, one to receive the curved points of the horizontal arm of the elbow-lever and the other to receive the forks on the upper end of governing-rod Q, which rod is jointed at its lower end to the horizontal lever S and steadied by the guide-bar R.

I is an angular or elbow lever forked at each extremity, the forks fitting the grooves easily in the respective thimbles F and G, and is hinged and supported at its angle by the projection H, extending from the axle C. It will now appear that the means of communicating governing power freely without binding or oblique bearing between the horizontal and vertical shafts is by the thimbles F and G and this two-forked lever, the thimble F being connected with the sails and the thimble G with the horizontal lever S, by which lever S the sails can be revolved on their stems, so as to present any desired degree of obliquity to the wind-current, or held in any desired position independently of the centrifugal

governing power of the balls P; or, if the lever S is left free, the balls P furnish a self-regulating power, which may be aided by weighting the lever S.

The power of the wind-wheel is communicated to the tubular column B by the cog-gear-wheels E on the pipe-box N operating the cog-wheel D on the tubular column.

Figs. 4 and 5 are sections of the center shaft A and axle C, showing the compact and simple device that takes the place of the broad-surfaced turn-tables in use for revolving the axes or shafts of wind-wheels in horizontal circles.

The enlargement of the axle C at its shoulder into the form of a hub or pipe-box c is so that the axis d of the shaft A may pass up directly through it, whereby the center of the axes of the shaft A and axle C intersect and in themselves form vertical and horizontal center bearings inside of the angle of the cog-gear-wheels D and E at the same time that the shaft A serves as a vertical bearing for the upper end of the tubular column B, to which is fastened the gear-wheel D, and the axle C is so formed that it serves as the axis e for the pipe-box N of the wind-wheel to revolve upon, to which pipe-box the gear-wheel E is fastened, the gear-wheels operating together freely as the wind-wheel is revolved horizontally in different directions. Thus two pieces, compact and durable, fitted together inside of or within the angle formed by the gear-wheels, and requiring no frame-work whatever to support them, entirely supersede the turn-tables composed of many parts supported by a frame-work and liable to be out of repair and out of true.

What I claim as my invention, and desire to secure by Letters Patent, is—

1. The peculiarly-constructed stationary central vertical shaft A, in combination with the peculiarly-constructed revolving tubular shaft or hollow column B, the shaft A providing axes for the wind-wheel and the tubular column B to revolve upon in the paths of horizontal circles and serving as a support and guide of the structure of the wind-wheel, and the tubular column B serving for receiving the power of the wind-wheel and transmitting it to machinery, substantially as set forth.

2. Enlarging the axle C at its shoulder in the form of a hub or pipe-box c, that the axis d of the shaft A may pass up directly through it, so that the center of the axes of the shaft A and axle C intersect and in themselves form vertical and horizontal center bearings within the angle formed by the gear-wheels D and E, and the shaft A and axle C also serve as bearings for the gear-wheels, substantially as and for the purposes set forth.

3. The combination of the horizontal lever S, the vertical governing rod or bar Q, guide-bar R, and thimble G on the tubular column, substantially as and for the purposes set forth.

4. The employment of a revolving conical

cover for the purposes of protecting the mechanism of the wind-wheel and dividing the wind-current at the front and center of the wind-wheel head and guiding it upon the sails and relieving the weighted elbow-levers used for revolving the sails on their radial axes of the countervailing influence of the wind-current, so as to enable them to act by

centrifugal force with certainty in governing the velocity of the wind-wheel, substantially as set forth.

JOHN M. MAY.
